(57) **CLAIM**

I claim the ornamental design for a portal for a model vehicle, as shown and described.

DESCRIPTION

FIG. 1 is an upper, right, rear perspective view of a portal for a model vehicle;

FIG. 2 is an upper, left, front perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is a reduced scale environmental bottom, left, front perspective view of a portal for a model vehicle mounted on a model vehicle platform.

In the drawings, the broken line showing of features of the portal for a model vehicle illustrates portions of portal for a model vehicle that forms no part of the claimed design; whereas, the broken line showing of the environmental use view depicts environmental subject matter and is provided for the purposes of illustrating environmental use structure and context and forms no part of claimed design.
